CLAIM

The ornamental design for a display screen with animated graphical user interface for interaction with a live-stream event, as shown and described.

DESCRIPTION

FIG. 1 is a front view of the first image in a sequence for a display with animated graphical user interface for interaction with a live-stream event showing the new design; FIG. 2 is a second image in the sequence that begins with the image of FIG. 1; FIG. 3 is a third image in the sequence that begins with the image of FIG. 1; and,

FIG. 4 is a fourth image in the sequence that begins with the image of FIG. 1.
The process or period in which one image transitions to another forms no part of the claimed design.

The broken lines in the drawings represent the display screen or portions thereof and elements of the graphical user interface that form no part of the claimed design.
